LOOSE LEAF BINDING

Vincenzo Catini, New York, N. Y.

Application August 7, 1935, Serial No. 35,052

10 Claims. (Cl. 129—1)

This invention relates in general to loose leaf bindings for stacks of sheeted material, that is to say, to bindings in which individual sheets may be removed from the binding without destroying the binding or the removed sheet, and in which sheets may be readily inserted. In particular it relates to bindings for such stacks of sheets, in which a binding element has a series of loop like members which are threaded through perforations provided

5 in the sheets of the stack, for the purpose of holding the sheets together in bound relation. Co-ordinately therewith, my invention relates to a method for producing such binding constructions.

In the particular form of my invention disclosed herein the successive loops are related to each other as are the coils of a helix. However, whereas in bindings employing a continuous helical binding element individual sheets may not be separated from the binding without removing the helix completely from the sheets, my invention 15 contemplates a binding construction having helically contoured loops in which individual sheets of the stack may be separately removed without destroying either the binding or the removed sheet, and in which sheets may be associated with the bound stack, without disturbing the binding. The provision of means for effecting this purpose is among the objects of my invention.

For the attainment of these objects and such other objects as will hereinafter appear or be 20 pointed out I have illustrated several embodiments of my invention in the drawing, in which:—

Figures 1 and 2 are views in perspective intended to illustrate the principles of my invention;

Figure 3 is a plan view of one embodiment of my invention;

Figure 4 is a sectional view thereof on the line 4—4 of Figure 3, looking in the direction of the arrows;

Figure 5 is a side elevation of another embodiment of my invention;

Figure 6 is a sectional view on the line 6—6 of Figure 5, looking in the direction of the arrows;

The principles underlying my invention can best be explained in connection with Figures 1 and 2. In Figure 1, A, B, C, D are intended to represent the successive coils of a helical element. Instead of being continuous however coil A is cut at a, coil B is cut at b, coil C is cut at c, and coil D is cut at d, and these cuts are arranged so that each successive cut is offset in relation to the preceding one, and in these figures the direction of offset is the same for the successive coils, although obviously this is not necessarily so. Assuming now

that these coils are held in fixed relation to each other, as, for example, by a member E uniting them, it will be found possible to insert a sheet S, having perforations P therein that register with coils of the spiral, into the openings, a, b, c, d and in causing the loops A, B, C, D to enter the perforations P, so that the sheet may assume the position shown in Figure 2. In order to insert the sheet S it is first necessary to warp it out of its normal plane in order to compensate for the aforementioned offsetting of the openings a, b, c, d. After the sheet has been inserted, with the coils of the spiral passing through the perforations P the sheet will tend to assume its normal plane conformation, with its inner edge substantially parallel to the axis of the coils of the helix, and when in that position it can not be readily disengaged from the coil, because only one perforation at a time will normally register with the opening in the coil passing through that perforation. This is clearly shown in Figure 2 in which the lower portions of the coils, adjacent the openings a, b, c, d project through said openings by an amount successively increasing. In order to remove the sheet S it is therefore again necessary to warp the sheet as shown in Figure 1, and after such warping has taken place the sheet may be slipped out through the openings a, b, c, d. It will therefore be obvious that a binding element constructed according to the principles just enunciated will effectively hold the sheets in bound relation and will permit ready removal or insertion of sheets by a simple manipulation, and without disturbing the binding of the other sheets.

The construction of Figures 3 and 4 may be arrived at by taking a continuous helically coiled wire and uniting it to a longitudinal member 10 in any suitable manner such as by soldering or welding, this wire being applied to one side of the coils of the helix. After such union by which the individual coils of the helix are held fixed to the member 10, the successive coils of the helix are cut as indicated at 12, and this cutting is shown as taking place along the line K—K that is curved in a spiral or helical direction in relation to the axis of the helix so that the cut in each coil is laterally displaced from the cut in the preceding coil. The result is a series of helically aligned coils 14 arranged in fixed relation along the connecting member 10 and each having an opening therein, and the successive openings are arranged in a line running spirally along the length of the binding element.

In the modification of Figures 5 and 6 the connecting member 10a is shown perforated as at

16 and the coils 14a are threaded through perforations 16a. Permanent assembly is again effected in any suitable or preferred manner such as by soldering or welding. Advantage of this 5 construction over the one of Figures 3 and 4 is that it has additional strength due to the fact that the union of member 10a and coil 14a depends not merely on the soldering or welding but on the added strength given by the 10 supporting effect of the walls of the holes 18a and of the spiral passing therethrough. The various coils are cut along a helical line as before, this being indicated at 12a. The method of assembly described in connection with Figures 3 15 and 4 is obviously also applicable to that of Figures 5 and 6.

While in connection with the above described 20 embodiments I have stated that the helical coils are permanently united to a connecting member, it will be obvious that this is not necessarily so, and that the coils may be removably held in place 25 as by clamping. It will also be obvious that while the helical arrangement of the openings is convenient for certain purposes, that for other purposes other arrangements will be found suitable, since to secure the desired locking action it is only necessary to offset some of the openings in 30 relation to the others. Again, while in the particular embodiment herein disclosed the coils are shown as forming parts of a single helix, this is not necessarily so, since the purposes of my invention will be attained with equal effect where the coils are not portions of the same helix.

It will further be understood that while I have 35 described a convenient method of assembly of the embodiments disclosed herein, namely the use of a helical coil which is united to a connecting member and then cut longitudinally, that it is not necessary to use this method of assembly. 40 For example, the individual coils 14 or 14a might first be completely prepared and then assembled with the connecting member 10 or 10a.

While I have herein disclosed several embodiments of my invention and indicated methods 45 of making such embodiments it is to be understood that my invention may be embodied in many other forms and may be practised in many other ways than those herein disclosed, and that the disclosure herein is by way of illustration 50 only and is not to be interpreted in a limiting sense, and that I do not limit myself in any way other than as called for by the prior art.

Having thus described my invention and illustrated its use, what I claim as new and desire 55 to secure by Letters Patent, is:—

1. A binding element for a stack of sheets comprising a series of open helical loops, said loops forming portions of a single helix and a member connecting said loops, and the opening in each 60 loop being peripherally offset with relation to the opening in the preceding loop, the direction of offset being the same for all of the loops.

2. As an article of manufacture, a binding element 65 for a stack of sheets comprising a series of helically aligned helical loops and a longitudinally extending member connecting said loops, an opening in each loop, said opening in each loop being peripherally offset with relation to the opening in the preceding loop, the direction and

amount of offset being the same for all of the successive loops.

3. As an article of manufacture, a binding element for a stack of sheets comprising a series of helically aligned helical loops and a longitudinally extending member connecting said loops, an opening in each loop, said opening in each 5 loop being peripherally offset with relation to the opening in the preceding loop, the direction of offset being the same for all the successive 10 loops.

4. A binding element for a stack of sheets comprising a series of open helical loops, said loops forming portions of a single helix and a member connecting said loops, and the opening in each 15 loop being peripherally offset with relation to the opening in the preceding loop, the direction of offset being the same for all of the loops, said connecting member having perforations therein, and said loops passing through said perforations. 20

5. The method of assembling a binding element for binding a stack of perforated sheets, that comprises the steps of uniting a helically coiled element with a member adapted to support the individual coils of the helix, and thereafter cutting an opening in each individual coil in such 25 a manner that the successive openings are arranged along a line spirally disposed with relation to the helix.

6. The method of assembling a binding element for binding a stack of perforated sheets, that comprises the steps of threading a helically coiled element through perforations in an elongated connecting member and uniting said element and member, and thereafter cutting an opening in 30 each individual coil in such a manner that the successive openings are arranged along a line spirally disposed with relation to the helix.

7. For use in binding together a stack of 35 perforated sheets, a binding element comprising a series of open helically contoured loops adapted to engage the perforations of the stack in threaded relation, the openings in at least one of said loops being offset in relation to another loop and means to hold said loops in a fixed 40 predetermined relation to each other.

8. For use in binding together a stack of 45 perforated sheets, a binding element comprising a series of open helically contoured loops adapted to engage the perforations of the stack in 50 threaded relation, the openings in said loops being offset in relation to the openings in the other loops and means to hold said loops in a fixed predetermined relation to each other.

9. For use in binding together a stack of 55 perforated sheets, a binding element comprising a series of open helically contoured loops adapted to engage the perforations of the stack in threaded relation, the opening in each of said loops being offset in relation to the openings in 60 the adjacent loops and a substantially rigid member uniting said loops.

10. For use in binding together a stack of 65 perforated sheets, a binding element comprising a series of axially aligned open helically contoured loops, all forming portions of the same helix, adapted to engage the perforations of the stack in threaded relation and means for holding said loops fixedly in said aligned relationships.

VINCENZO CATINI.
